CLAIM

The ornamental design for a housing for hand held optical scanner, as shown and described.

DESCRIPTION

FIG. 1 is a perspective view of a housing for hand held optical scanner showing our new design;
 FIG. 2 is a left side elevational view thereof, the right side being a mirror image thereof;
 FIG. 3 is a top plan view thereof;
 FIG. 4 is a bottom plan view thereof;
 FIG. 5 is a front elevational view thereof; and,
 FIG. 6 is a rear elevational view thereof.
